APPARATUS FOR MANUFACTURING
COVERED BELT BUCKLESSamuel Levin, New York, and Louis Rosenberg,
Brooklyn, N. Y.

Application June 30, 1938, Serial No. 216,774

3 Claims. (Cl. 29—3)

This invention relates to improvements in covered belt buckles and method and apparatus for manufacturing the same.

In conventional covered belt buckles a hollow frame surrounding a belt-receiving opening or aperture is composed of top and bottom reinforcing shells of metal or like rigid material having edge flanges, and these shells are covered by a suitable flexible covering material, the covering material in the manufacturing operation being initially folded around both the outer and inner flanges at the edges of each of the shells, after which the flanges at the outer and inner edges of the top and bottom shells so covered are frictionally fastened together by a suitable die to interlock the shells and to fasten both the inner and outer edges of the flexible covering material between the flanges or edges of the shells or reinforcing members, while the flanges along the belt-receiving opening were forced into close abutment. In the said manufacturing operation, a die is usually employed in which core members having the shape of the belt-receiving opening and outer rim members having the shape of the outer edge of the buckle are moved into interengaging movable relationship to a pressure-applying head while the intermediate shell-contacting portions remain in stationary position with relation to such head during the clinching action of the head on the buckle frame. This mechanism, though effective in clinching the edges both along the belt-receiving opening and the outer edge of the buckle, made it impossible to utilize extension edges at the outer edge of the buckle or to ornament such outer edges.

One of the objects of our present invention is to enable covered buckles to be made with extension edges of any suitable shape or ornamental design by suitable mechanical apparatus and to provide, in such apparatus, for a clinching action between upper and lower reinforcing members at the edge of the belt-receiving aperture or inner edge of the frame members while at the same time providing an extension outer edge of any suitable ornamental design or shape by pressing and fastening the top and bottom portions of covering material along a strip closely adjacent to the outer edge of the frame and allowing the outer edges of such covering members to project outwardly from the reinforcing members. In making these buckles practically from a commercial standpoint, dies must be employed, and in such dies, instead of retaining the intermediate shell-contacting members in

stationary position in relation to the pressing head and utilizing rim and core members which move in relation to said head and shell-contacting members, we retain the rim and core members in stationary relationship to the pressure-applying head and provide for a resilient movement of the upper frame-contacting intermediate member in relation to said head and to relatively stationary core and rim members. By 10 retaining the rim member in stationary relationship to the pressure-applying head, we are enabled simultaneously to provide for an outward extension and pressing of the outer edges of the covering members and for a clinching action 15 between the edges of the top and bottom shells at the edges of the belt-receiving aperture and by providing for a relative movement of a frame-contacting member we are enabled to produce a covering member prior to the pressing and fastening action of the two covering members. By 20 retaining the rim members in stationary position, we also leave space in the plane of the meeting covering edges to enable outward extension and ornamentation thereof in any suitable 25 way, as for example by scalloping or providing saw teeth at the edges or by leaving elongated projecting portions which may, in conformation, be dove-tailed or of any other suitable shape.

Another object of this invention is to enable 30 the production of belt buckles having top and bottom reinforcing frame members of rigid material covered by a suitable flexible covering material, the top and bottom members of which 35 are clinched between the reinforcing frame members around the edges of the inner belt-receiving opening and having the opposite outer edges of said members of covering material extending outwardly in abutment and having a lapped joint 40 with each other without being clinched between the outer edges of the reinforcing members, said lapped joint being formed by a pressing between abutting rim members of the apparatus and a fastening together, preferably by cement 45 or the like, of such outer edges, such outer edges being formed in any suitable shape or design and when so fastened together forming a highly ornamental and rigid belt buckle.

Another object of our invention is to produce, 50 by a mechanical process, a belt buckle structure of the type specified, having its cover members provided with outwardly extending edges capable of being ornamented whereby such outwardly extending edges are, in a single operation, initially bent downwardly over the outer edges of

the shell and then pressed and fastened together in a plane coinciding with the bottom of the belt buckle, and with this end in view, we provide a cover fastening mechanism embodying a die element having pressing rim portions capable of pressing the edges of the cover members combined with intermediate frame-contacting die portions one of which will be movable in relation to the other to provide for a simultaneous bending of the outer edge and a clinching of inwardly folded cover members along the inner edge of the belt-receiving aperture.

With these and other objects in view, the invention comprises the combination of members and arrangement of parts so combined as to coact and co-operate with each other in the performance of the functions and the accomplishment of the results herein contemplated, and comprises in one of its adaptations the species or preferred form illustrated in the accompanying drawings, in which:

Fig. 1 is a view in plan of one of two metal shells used in making our covered belt buckle;

Fig. 2 is a view in plan of the under-side of the shell shown in Fig. 1;

Fig. 3 is a view in plan of one of two similar cover members used in covering a pair of shells such as shown in Figs. 1 and 2;

Fig. 4 is a view in plan of a completed belt buckle embodying our invention;

Fig. 5 is a view, partly in side elevation and partly in section, of a press shown in the operation of fastening the upper shell and cover members to the upper core portion of the press head;

Fig. 6 is a view similar to Fig. 5 with the press head and bed separated to show the upper shell and cover members frictionally fastened to said core portion;

Fig. 7 is a view partly in elevation and partly in section similar to Fig. 5, showing the press, with an intermediate member inserted between the head and bed, in the operation of fastening the lower shell and cover members to the lower core;

Fig. 8 is a view of the press shown in Fig. 7, with the intermediate member inverted and the upper and lower shells and cover members assembled and ready for the clinching and pressing operation;

Fig. 9 is a view similar to Fig. 8, showing the parts pressed together to complete the buckle;

Fig. 9^a is a fragmentary view of a portion of the press shown in Figs. 7 and 9, the section being taken at right angles to that shown in Fig. 9;

Fig. 10 is a fragmentary cross section of a completed belt buckle removed from the press;

Fig. 11 is a view in plan of a modified form of buckle embodying our invention and showing a supplemental frame along the edges of the belt-receiving opening;

Fig. 12 is a view in plan of another modified form of belt buckle embodying our invention; and

Fig. 13 is a fragmentary section on the line 13—13 of Fig. 11, looking in the direction of the arrows.

Referring now to these drawings which illustrate a preferred embodiment of our invention, Fig. 1 indicates, in top elevation, a member of a pair of conventional shells used in making belt buckles. Such shells are conventionally provided, at their peripheries, with interengaging rim flanges 2 and preferably have tongue-post sections 5 separating a belt-receiving aperture into two parts 3, 3'. The belt-receiving apertures of

the two members are also provided with flanges 4. In the preferred embodiment of our invention illustrated, a pair of these shells comprising an upper shell and a lower shell, which are adapted to seat one within the other, are covered with a pair of substantially identical cover members 6, (Fig. 3). These cover members are provided with belt-receiving openings 3^a registering with the shell apertures and have, along their marginal edges, flaps 7 so cut as to be foldable over the internal aperture flanges of the shell. In the present embodiment of our invention, the cover members 6 are preferably provided at their outer perimeters with ornamental edges 8 which, in Figs. 3 and 4, we have shown as circular and serrated while in Figs. 11 to 13 a square shape and a shape of dovetail conformation is shown.

The edges 8 of the members 6 have outwardly extending perimetric portions which are not folded inwardly but are extended outwardly to provide abutting flanges 8' which are connected together by a pressed joint. In Fig. 4, this pressed joint extends around the perimeter 8' of the circular shells, while in Fig. 11 the joint extends along the marginal edge 8^a of a square shell and in Fig. 12 this joint extends along the rounded portions 8^b, 8^b' and along the dove-tailed portions 8^c, 8^c', the edges of all of which are preferably serrated or otherwise ornamented.

In accordance with our present invention we are enabled, by mechanical means, not only to produce belt buckles having outwardly extended perimetric portions which are capable of themselves being ornamented and of providing ornamentation for the belt buckle but of producing such belt buckles with top and bottom shells which add to the rigidity of the belt buckle structure and with this end in view, we provide a novel process and apparatus for making a belt buckle embodying top and bottom reinforcing members or shells covered with upper and lower cover members each provided with belt-receiving apertures and having their edges at such apertures folded around their respective edges of the belt-receiving aperture in the frame members. These shell members are utilized not only to reinforce the buckle when completed, but also are employed, during the manufacturing operation, to support the cover members in proper relationship to permit the cover members to be clinched around the edges of the shells at the belt-receiving aperture and locked together by pressing of the shells into interengagement and providing a pressed joint at the outer edges thereof, all in a single operation.

In the preferred form of our invention, the joint formed by clinching of the cover members between the interengaged shell flanges at the belt-receiving aperture is, in the conventional manner, formed within planes coinciding with the top and bottom of the shell members while the pressed joint at the outer edge of the belt is formed in a plane substantially coinciding with the bottom surface of the lower shell member, so that when the belt is in use this outwardly extending portion will lie flat against the body of the wearer. Also, in the preferred embodiment of our invention, the perimetric flanges of the shell members are preferably clinched together within the belt buckle adjacent to the pressed joint hereinabove referred to.

In accordance with our invention, we take a rigid top frame member, support in registering position thereon a top cover member, then place

the same in a press, as shown in Figs. 5 and 6, and frictionally connect the said shell with its cover member beneath the head member of the press. We then, by a similar operation, connect the bottom member frictionally beneath an intermediate reversible member of the press. This reversible member is then inverted to cause the flange portions of the shells to extend toward each other. Thereafter pressure is applied on the head to cause, in one operation, the clinching of the covers between the flanges along the belt-receiving aperture and at the same time pressing the outer extension portion of the covers together to provide a pressed joint along such outer edges and also preferably during the same operation, forcing the engaged flanges at the outer peripheries of the shells, into an interlocking engagement within the belt.

In the preferred embodiment of our invention illustrated, we provide a press 9, comprising a conventional base member 10 and a novel head 11. This novel head embodies an outer rim-pressing member 12, a central core member or plug 13 and an intermediate body contacting member 14. In the embodiment shown, the pressing member 12, is fast on the head 11 while the core member 13 and intermediate member 14 are relatively removable in relation thereto and also relatively removable in relation to each other. In the initial operation illustrated in Figs. 1 and 2, 5 and 6, a top shell member 1 is supported on a bed 10', with its perimetric flange 2 extending into a groove 10^a, while its inner flanges 4 extend into an opening 10^b. A top cover 6 is supported on the shell member 1 with its outwardly-extending portion 8' projecting outwardly beyond the flange 2 and being supported within a perimetric groove 10^c. The head 11 of the press is then brought into contact with the base portion 10, while all of the parts of the head are locked into stationary relationship, the intermediate member of the press 14 being held within the head by a pin 14^b (see Fig. 9^a) which is engaged by a lever 14^a having a notch 14^b adapted to engage the pin 14^b so as to hold the member 14 from moving downwardly during the initial operation of connecting the top shell and cover member beneath the press head. When the intermediate member is thus held and the head applied on the base member 10, a pressure exerted, by any suitable means, not shown, on the head will exert pressure against the spring 14' and will cause the core member 13 to move downwardly relatively to the intermediate member so as to force the flanges 7 of the cover member against the flanges 4 of the shell member and to provide a frictional connection between such flanges and the plug member 13, so that upon raising or elevating the head 11 out of contact with the base member, as shown in Figs. 6, 7 and 8, the top shell and the top cover member will be held in elevated position beneath the head member, it being understood that on the application of such pressure, the lever 14^a will lock the pin 14^b and hold the member 14 in elevated position.

We now make a similar operation in relation to the lower member. In so doing we insert, on the bed of the press, an intermediate reversible press member 16 which embodies a bed portion 16' and a central core portion or plug 17, as more particularly shown in Fig. 7. Upon similarly ap-

plying pressure on the core member or plug 17, by the head 11, a bottom shell member 1^a and a bottom cover member 6^a will be similarly frictionally fastened beneath the intermediate member 16, it being understood that during this operation the core member 13 will be locked against upward movement in relation to the head so that it may apply pressure on the core member 17. This locking of the core member is preferably accomplished by the provision of a cross member 18 connected to the core member and locked against upward movement by arms 19, 19'. Upon moving the head 11 and reversing the intermediate member 16 into the position shown in Fig. 8, the top and bottom shells and top and bottom cover members will be brought into proper connectible relationship to each other in which the flanges of the shells are extended toward each other. Now by applying pressure to the head and bringing the parts into the position shown in Figs. 9 and 9^a, the arms 14^a and 19' will be released and the flanges of the shells at the belt-receiving aperture will be clinched together as shown in Figs. 9, 9^a and 10, while the outwardly-extending edges of the cover members will be pressed together to form a pressed joint. During this operation the member 14, will rise slightly against the action of the springs 14' and the pressed joint will be formed in a plane substantially coinciding with the lower surface of the bottom shell. During this operation, the inner edge of the member 12 will press the outer flange of the upper shell into interlocking engagement with the lower flange.

The buckle can now be removed from the press and will be complete with clinched joints along the belt-receiving aperture and a pressed joint around the outer edge.

Having described our invention, we claim:

1. Apparatus for manufacturing covered belt buckles embodying, in combination, a die bed and a clinching head comprising an outer rim member, a core member and an intermediate frame-contacting member one of said clinching head members being movable in relation to the other for the purpose hereinabove specified.

2. Apparatus for manufacturing covered belt buckles embodying, in combination, a die bed and a clinching head comprising an outer rim member fixed in relation to said head, a core member and an intermediate frame-contacting member one of said clinching head members being movable in relation to said rim member for the purpose hereinabove specified.

3. Apparatus for manufacturing covered belt buckles embodying, in combination, a die bed and a clinching head comprising an outer rim member fixed in relation to said head, a core member and an intermediate frame-contacting member, one of said clinching head members being movable in relation to said rim member for the purpose hereinabove specified, said core member being also retained in stationary relationship to said head and movement of one of said clinching head members being adapted, in one operation, to clinch the folded edge portions of the cover members at the belt-receiving aperture and to apply pressure on extended outer edges of the cover members.

SAM LEVIN.
LOUIS ROSENBERG.
